UNITED STATES PATENT OFFICE.

ANTONI JANIECZ, OF CURTIS BAY, MARYLAND.

DESIGN FOR A HAIRPIN.

55,052.

Specification for Design.

Patented May 4, 1920.

Application filed February 10, 1920. Serial No. 357,682. Term of patent 7 years.

To all whom it may concern:

Be it known that I, ANTONI JANIECZ, a citizen of Poland, residing at Curtis Bay, in Baltimore City and State of Maryland, have invented a new, original, and ornamental Design for a Hairpin, of which the following is a specification, reference being had to the accompanying drawing, forming part thereof.

The figure is a front elevational view of a hair pin, showing my new design.

I claim—

The ornamental design for a hairpin, as shown.

ANTONI JANIECZ.
